VERTICAL ELECTRIC MOTOR OR THE LIKE

Arlin C. Eisenhart, Fullerton, Calif., assignor to U.S. Electrical Motors, Inc., Los Angeles, Calif., a corporation of California

Filed Jan. 24, 1961, Ser. No. 63,683

Term of patent 14 years

(Cl. D26—5)

FIG. 1.

FIG. 2.

FIG. 3.

FIGURE 1 is a front elevational view of a vertical electric motor or the like, showing my new design;

FIG. 2 is a side elevational view thereof; and

FIG. 3 is a top plan view thereof.

I claim:

The ornamental design for a vertical electric motor or the like, substantially as shown.
